1 Claim

ABSTRACT OF THE DISCLOSURE

Compounds of the formula

wherein R is H, —OCH₃, or —Cl

R₁ is

or

and the citrate and hydrochloride salts thereof. These compounds have pharmaceutical utility by virtue of their antitussive activity.

This invention relates to some new salts of amino-alkyl- and aminoalcoxyalkyl esters of α -phenoxy-isobutyric, α -(o'-methoxy-phenoxy)-isobutyric and α -(o'-chlorophenoxy)-isobutyric acid, the process of preparing said compounds and to the therapeutical use thereof.

These new compounds may be represented by the following general formula:

2

wherein

R is H, —OCH₃, or —Cl

5 R₁ is

45 One object of the present invention consists of the substances indicated by the Formula 1 and characterized as salts (hydrochlorides or citrates), in as much as they are new products, never obtained before by synthesis, nor described in literature.

50 A further object of the present invention consists of a process of synthesis which leads to the compounds represented by Formula 1.

Still another object of the present invention relates to the therapeutical application of the said compounds. In fact, these derivatives have shown in the experimental animals, besides a low toxicity, an antitussive action like that of codeine, but without causing the well-known side effects of the substance.

55 As an example, the following are some of the pharmaceutical properties of the salts which are the object of the present invention.

The lethal oral dose in the rat, of the compounds which are the object of the present invention is in the range between 4000 and 8000 mg./kg.

60 The administration by mouth to rats of the compounds represented by Formula 1, in doses varying from 400 to 800 mg./kg. daily for 50 days, has not revealed variations of the body weight growth curve, of the reactivity, of the appetite, of the excretion and nature of urine and feces. Nor were any variations detected in the number and 65 morphological characters of the red blood corpuscles, leukocytes, blood clotting time and hematocrit value.

The compounds which are the object of this invention, when introduced through the gastric passage in experimental animals, even in doses higher than the therapeutic ones, have never caused either a decrease in speed of the intestinal transit, unlike codeine whose constipation effect is particularly evident, or a depressive effect on respiration.

Most of the products represented by Formula 1 have shown a decrease in coughing, when administered by mouth in suitable doses to suitably treated rats.

Due to their particular antitussive activity, low toxicity, and lack of unfavorable side effects, the compounds of the present invention can be usefully applied in therapy, both alone as well as in association with other products.

The synthesis process of the compounds represented by Formula 1 consists schematically in reacting in a suitable boiling solvent, the chlorides of α -phenoxy-isobutyric, α -(α' -methoxy-phenoxy)-isobutyric, and α -(α' -chlorophenoxy)-isobutyric acid with the aminoalcohols and aminoalkoxyalcohols corresponding to the desired product, in the presence of an organic base (for example, triethylamine). The esters, obtained as oily liquids, are transformed into salts (for example hydrochlorides or citrates) by treating them with the relative acids.

The following examples serve to illustrate more fully the new compounds as obtained according to this invention, and their methods of preparation. However, it is understood that such examples have only an illustrative and not a limitative nature, since variations of the schemes given in the examples will be obvious to the experts in the art, and therefore they should be considered as comprised in the field of the invention.

Example 1

A solution of 198 g. α -phenoxy-isobutyric acid chloride in 500 ml. anhydrous benzene is added, slowly and under stirring, while maintaining the temperature at 25° C. to a solution of 131 g. β -morpholinoethanol and 202 g. triethylamine in 1500 ml. anhydrous benzene. The mixture is then heated at boiling point for 4 hours always under stirring; thereafter, it is filtered hot and the solvent is stripped at 15 mm. and 40° C.

The reaction product is purified by distillation at 0.01 mm. and 127–130° C.

The β -morpholinoethyl ester of α -phenoxy-isobutyric acid, as obtained, is transformed into the corresponding hydrochloride by dissolving 230 g. of it in 600 ml. absolute ethanol and by passing through the solution a current of gaseous hydrochloric acid until a pH of 2 is reached. By adding 1000 ml. anhydrous ethyl ether and leaving at 0° for 12 hours there are obtained crystals of β -morpholinoethyl ester of α -phenoxy-isobutyric acid hydrochloride; M.P. 143–145° C.

Example 2

Similar to Example 1, by reacting in the same conditions 89.1 g. dimethylamino-ethanol and 198 g. α -phenoxy-isobutyric acid chloride there is obtained the β -dimethylamino-ethyl ester of α -phenoxy-isobutyric acid; B.P. at 0.03 mm. 93° C.

This ester, when dissolved in 95% ethanol and treated with an equimolar amount of citric acid, by adding a double volume of ethyl ether and leaving for 12 hours at 0°, yields the citrate of the β -dimethylamino-ethyl ester of α -phenoxy-isobutyric acid; M.P. 98–99° C.

Example 3

177 g. diethylamino-ethanol is reacted in the conditions described in Example 1 with 198 g. α -phenoxy-isobutyric acid chloride to yield the β -diethylamino-ethyl ester α -phenoxy-isobutyric acid, at 0.01 mm. 107° C. B.P. which, when treated with an equimolar amount of citric acid in alcohol solution as in Example 2, yields the corresponding citrate, M.P. 134–135° C.

Example 4

Example 1 is repeated but by reacting 129 g. β -piperinoethanol with 198 g. α -phenoxy-isobutyric acid chloride to yield the β -piperinoethyl ester of α -phenoxy-isobutyric acid, which is purified by distilling at 0.01 mm. and 125° C.

This ester is transformed into the citrate in the manner described in Example 2. This citrate of the β -(N-piperine)-ethyl ester of α -phenoxy-isobutyric acid melts at 75–78° C.

Example 5

By the same method as described in Example 1, 133 g. β -(2-dimethylamino-ethoxy)-ethanol is reacted with 198 g. α -phenoxy-isobutyric acid chloride to yield the β -(2-dimethylamino-ethoxy)ethyl ester of α -phenoxy-isobutyric acid; B.P. 128° C. at 0.01 mm.

This ester is transformed into the citrate by treating with citric acid in alcoholic solution as described in Example 2: M.P. 84–85° C.

Example 6

161 g. β -(2-diethylamino-ethoxy)-ethanol is treated with 198 g. α -phenoxy-isobutyric acid chloride, as described in Example 1 to yield the β -(2-diethylamino-ethoxy)ethyl ester of α -phenoxy-isobutyric acid, B.P. 120° C. at 0.01 mm.

This is transformed into the citrate in the same manner as described in Example 2: M.P. 83–84° C.

Example 7

By the same method described in Example 1, 175 g. β -morpholinoethoxyethanol is reacted with 198 g. α -phenoxy-isobutyric acid chloride to yield the β -morpholinoethoxyethyl ester of α -phenoxyisobutyric acid, boiling point 130° C. at 0.01 mm. This is treated with citric acid, as described in Example 2, to yield the corresponding citrate, M.P. 100–102° C.

Example 8

40 A solution of 228 g. α -(α' -methoxy-phenoxy)-isobutyric acid chloride in 500 ml. anhydrous benzene is added, at 25° C. and under stirring, to a solution of 129 g. β -piperidinoethanol and 202 g. triethylamine in 1500 ml. anhydrous benzene. After heating at boiling point for 4 hours, the mixture is filtered through a paper filter and the filtrate is distilled first at 40° C. and 15 mm. in order to separate the solvent and then at 132–134° C. and 0.01 mm. in order to isolate the pure product, that is to say, the β -piperidinoethyl ester of α -(α' -methoxy-phenoxy)-isobutyric acid.

45 A solution of 225 g. of the ester, as obtained, in 500 ml. absolute ethanol is added to a solution of 134.5 g. citric acid in 300 ml. absolute ethanol. The mixture is stirred, 1500 ml. anhydrous ether is added and the whole is kept at 0° for 12 hours.

50 Thus, the citrate of the β -piperidinoethyl ester of α -(α' -methoxy-phenoxy)-isobutyric acid is obtained. Melting point 54–56° C.

Example 9

60 By the same method as described in Example 8, 89.1 g. dimethylamino-ethanol is reacted with 228 g. α -(α' -methoxy-phenoxy)-isobutyric acid chloride to yield the β -dimethylamino-ethyl ester of α -(α' -methoxyphenoxy)-isobutyric acid, having a boiling point of 118° C. at 0.01 mm.

65 This ester is treated in alcoholic solution with citric acid, as indicated in Example 8, to yield the corresponding citrate having a M.P. 86–88° C.

Example 10

70 117 g. diethylamino-ethanol is reacted in the same conditions as described in Example 8, with 228 g. α -(α' -methoxy-phenoxy)-isobutyric acid chloride to yield the β -diethylamino-ethyl ester of α -(α' -methoxy-phenoxy)-

isobutyric acid, having a B.P. of 128° C. at 0.01 mm. By treating this ester with citric acid, as indicated in Example 8, the corresponding citrate is obtained, having a M.P. of 106–108° C.

Example 11

By reacting 131 g. morpholinoethanol with 228 g. α -(o'-methoxy-phenoxy)-isobutyric acid chloride in the conditions described in Example 8, there is obtained the β -morpholinoethyl ester of α -(o'-methoxy-phenoxy)-isobutyric acid, having a B.P. of 134° C. at 0.01 mm. This is treated with citric acid to yield the corresponding citrate having a M.P. of 100–102° C.

Example 12

Following Example 8, 133 g. β -(2-methylaminoethoxy)-ethanol is reacted with 228 g. α -(o'-methoxyphenoxy)-isobutyric acid chloride to yield the β -(2-dimethylaminoethoxy)-ethyl ester of α -(o'-methoxyphenoxy)-isobutyric acid, having a B.P. of 133° C. at 0.01 mm.

This ester is transformed to the citrate as described in Example 8, and the corresponding salt melts at 70–71° C.

Example 13

161 g. β -(2-diethylaminoethoxy)-ethanol is treated with 228 g. α -(o'-methoxy-phenoxy)-isobutyric acid chloride, as described in Example 8, to yield the β -(2-diethylaminoethoxy)-ethyl ester of α -(o'-methoxyphenoxy)-isobutyric acid having a B.P. of 137° C. at 0.02 mm.

By treating this ester with citric acid, as indicated in Example 8, the corresponding citrate is obtained having a M.P. of 80–81° C.

Example 14

By the method described in Example 8, 175 g. β -morpholinoethoxyethanol is reacted with 228 g. α -(o'-methoxyphenoxy)-isobutyric acid chloride to obtain the β -morpholinoethoxyethyl ester of α -(o'-methoxyphenoxy)-isobutyric acid, having a B.P. of 145° C. at 0.01 mm.

This ester is saponified with citric acid as indicated in Example 8, to yield the citrate having a M.P. of 77–79° C.

Example 15

133 g. β -(2-dimethylaminoethoxy)-ethanol and 202 g. triethylamine are dissolved in 1500 ml. anhydrous benzene; then, a solution of 233 g. α -(o'-chlorophenoxy)-isobutyric acid chloride in 500 ml. anhydrous benzene is added slowly under stirring at a temperature of 25° C. The mixture is warmed to boiling point for 4 hours, under stirring; then, it is filtered hot and the solvent is stripped at 15 mm. and 40° C.

The crude β -(2-dimethylaminoethoxy)-ethyl ester of α -(o'-chlorophenoxy)-isobutyric acid, as obtained, is purified by distilling it at 0.02 mm. and 130–135° C.

250 g. of the pure product is dissolved in 500 ml. absolute ethanol and is treated with a solution of 146 g. citric acid in 300 ml. absolute ethanol; then, 1500 ml. anhydrous ether is added and the whole is left for 12 hours at 0° to yield the citrate of the β -(2-dimethylaminoethoxy)-ethyl ester of α -(o'-chlorophenoxy)-isobutyric acid, melting at 73–75° C.

Example 16

Analogously to Example 15, 89.1 g. dimethylaminoethanol is reacted with 233 g. α -(o'-chlorophenoxy)-isobutyric acid chloride to yield the β -dimethylaminoethyl ester of α -(o'-chlorophenoxy)-isobutyric acid having a B.P. of 123° C. at 0.01 mm.

By treating this ester in alcoholic solution with an equimolar amount of citric acid there is obtained the citrate of the β -dimethylamino-ethyl ester of the α -(o'-chlorophenoxy)-isobutyric acid having a M.P. of 88–90° C.

Example 17

117 g. diethylamino-ethanol is reacted in the same conditions as described in Example 15, with 233 g. α -(o'-chlorophenoxy)-isobutyric acid chloride to yield the β -diethylamino-ethyl ester of α -(o'-chlorophenoxy)-isobutyric acid having a B.P. of 126° C. at 0.01 mm. This is treated in alcoholic solution with an equimolar amount of citric acid to yield the corresponding citrate having a M.P. of 131–133° C.

Example 18

129 g. piperidinoethanol is treated with 233 g. α -(o'-chlorophenoxy)-isobutyric acid chloride, as described in Example 15, to yield the β -piperidinoethyl ester of α -(o'-chlorophenoxy)-isobutyric acid having a B.P. of 132° C. at 0.02 mm.

The citrate, obtained as in Example 8, has a M.P. of 62–66° C.

Example 19

As in Example 15, 131 g. morpholinoethanol is reacted with 233 g. α -(o'-chlorophenoxy)-isobutyric acid chloride to yield the β -morpholinoethyl ester of α -(o'-chlorophenoxy)-isobutyric acid having a B.P. of 142° C. at 0.01 mm.

This ester is transformed into the citrate by treating it with citric acid as described in Example 15; M.P. 85–87° C.

Example 20

As in Example 15, 161 g. β -(2-diethylaminoethoxy)-ethanol is reacted with 233 g. α -(o'-chlorophenoxy)-isobutyric acid chloride, to yield the β -(2-diethylaminoethoxy)-ethyl ester of α -(o'-chlorophenoxy)-isobutyric acid, having a B.P. of 138° C. at 0.01 mm.

The corresponding citrate has a M.P. of 72–74° C.

Example 21

By the same method as described in Example 15, 175 g. β -morpholinoethoxyethanol is reacted with 233 g. α -(o'-chlorophenoxy)-isobutyric acid chloride to yield the β -morpholinoethoxyethyl ester of α -(o'-chlorophenoxy)-isobutyric acid having a B.P. of 139° C. at 0.02 mm. This ester is treated with citric acid, as described in Example 15, to yield the corresponding citrate having a M.P. of 75–77° C.

I claim:

1. The hydrochloride or citrate salt of the β -morpholinoethyl ester of α -phenoxy-isobutyric acid.
